EDWARD KIRBY BOTTLE, OF ELMIRA, NEW YORK, ASSIGNOR TO AMERICAN SALES BOOK COMPANY, LIMITED, OF TORONTO, ONTARIO CANADA, A CORPORATION OF ONTARIO.

MANIFOLDING SALES BOOK.

Application filed May 23, 1922. Serial No. 562,955.

This invention relates to manifolding devices and with respect to its more specific features to manifolding books, pads and the like.

5 One of the objects of the invention is the provision of a practical manifolding device adapted to be utilized in manifolding books for making a plurality of, as from four to six, records at one writing, and wherein 10 the construction and the relation between the record leaves and the transfer leaves provides for convenient manipulation and setting of the book notwithstanding the large 15 number of records to be simultaneously made.

Other objects will be in part obvious and in part pointed out hereinafter.

The invention accordingly consists in the features of construction, combinations of 20 elements and arrangement of parts which will be exemplified in the construction hereinafter set forth, and the scope of the application of which will be indicated in the following claim.

25 In the accompanying drawing forming part of the specification and wherein similar reference characters refer to similar parts throughout the several views,

Figure 1 illustrates, in perspective, an embodiment of the invention designed for 30 making six records at one writing;

Fig. 2 is a side elevation of Fig. 1, partly in section;

Fig. 3 diagrammatically illustrates in 35 perspective, a modification of Fig. 1, adapted for making six records at one writing;

Fig. 4 is a further modification adapted for making five records; and

Fig. 5 is a still further modification 40 which may be utilized for making four records.

Referring now more specifically to the drawings and particularly to Fig. 1 thereof, the numeral 1 indicates a pad of record leaves of such material, as paper, that 45 when the leaves are superposed one upon another with the interposition of transfer material a writing made upon an upper leaf will be transferred to the underlying leaves.

In the embodiment now referred to 50 these leaves are relatively opaque and four opaque direct copies are made at one writing. It will be understood that transparent

material, as tissue paper, may be employed.

The pad 1 is composed of a plurality of 55 superposed record sheets bound together at one end by the staples 2. As all of these sheets are alike, a description of one will suffice. One of these sheets is shown in open condition in Fig. 1, and is composed of the four leaves 3, 4, 5 and 6, the leaves 3, 5 and 6 being of substantially the same length and width, the leaf 4 having an extended or stub portion 7 for binding purposes, and being weakened along the line 8 in order that it may be readily torn from the stub portion.

Each of the record sheets is formed from 60 a strip which is first folded along the line 9 to provide a folded record sheet of two plies. Thereupon this folded, or two ply, sheet is again folded intermediate its ends on lines parallel with the line 9, that is, between the folded end 9 and the end constituting the free ends of the original sheet, as generally indicated at 10, so as to provide the four relatively superposed record leaves 65 3, 4, 5 and 6 above referred to. To the underface of the original leaf 3 is pasted a supplemental, preferably transparent, record leaf 11, the pasted area being indicated by the shading at 12, this area being at one side 70 of the folding line 9. The supplemental leaf 11 lies in superposed relation to the original leaf 3 and when the book is set 75 for operation as illustrated in Fig. 1, this supplemental leaf is in superposed relation to the four leaves 3, 4, 5 and 6. It will be understood that the showing in Fig. 1 is mainly diagrammatic in order to clearly disclose the relative arrangement of the parts.

In the actual manifolding pad the fold line 80 between the leaves 5 and 6 will be closely adjacent so as practically to be identical with the fold line between the leaves 3 and 4. 85 The numeral 13 indicates a backing which may be made of pasteboard or other relatively stiff substantial material, and the bound end of the pad 1 may be held to the backing 13 by prolonging the staples 2 for 90 the purpose. Or separate staples may be employed.

The numeral 14 indicates an extension of 95 the backing 13, the extension being hinged to the backing as by means of the flexible connection 15, the axis of this hinge being 100

parallel to the adjacent stub of the pad 1. Near the hinge 15 a supplemental pad composed of tissue leaves is removably fastened to the extension 14 as by being stapled thereto. The leaves of the supplemental pad are indicated at 16, one of these leaves being shown as in superposed relation to the leaves of the pad 1.

In the present embodiment the transfer material, which is adapted to transfer inscription from one to another of the superposed record leaves, includes the transfer leaves 17 and 18. The transfer leaf 17 is bound in the pad with the record leaves 4 and is of sufficient length to extend across that fold line of the uppermost record sheet consequent from the intermediate folding; i. e., it extends across the fold line formed by folding the two-ply sheet above referred to. As illustrated, it is substantially co-extensive with the length of two connected record leaves. The transfer leaf 18, when in operative position, is adapted to lie between the record leaves 5 and 6 and works on an axis 25 at an angle to the bound end of the pad. In the embodiment illustrated the transfer leaf 18 is stapled to the backing 13, as for instance indicated at 30, Fig. 4, and extends from the side of the backing so that its working plane 30 is substantially at right angles to the longitudinal dimension of the pad 1. The transfer leaf 18 may proceed from either the right side or the left side of the backing 13, although the left side is preferred. In the embodiment of the invention illustrated in Fig. 1 the long transfer leaf 17 is folded along the line 19 which is substantially coincident with the fold line 10, providing two transfer leaf sections 20 and 21; also in the same embodiment each of the sections 20 and 21 is coated with transfer material on both faces so as to transfer impressions direct to the record leaves 4 and 5 and reverse to the supplemental record leaf 11 and the supplemental tissue leaf 16. That face of the transfer leaf 18 which is adapted to lie against the record leaf 5 is coated with transfer material, the opposite face thereof being preferably uncoated. To facilitate the grasping of the book while manipulating the leaves, the backing 13 may be made sufficiently long to provide an area for supporting substantially the full longitudinal extent of the two-ply record sheet hereinbefore referred to. The prolonged portion is indicated by the numeral 31.

In the modification illustrated in Fig. 3, the supplemental pad of tissue leaves, instead of working from the bound end of the main pad 1, works from that side of the main pad opposite the side from which the transfer leaf 18 works. In such instance, the backing 13 may have a hinged lateral extension 22, to which is fastened a metallic clip

having resilient jaws 23 and 24 between which is firmly but removably grasped the stub end of the pad of leaves 16.

The construction illustrated in Fig. 4 is identical with that illustration in Fig. 1 except that no supplemental pad of leaves 16 is used. By consequence the hinged extension 14 is also eliminated. With this form five records are made at one writing.

In the modification illustrated in Fig. 5 the construction is identical with that illustrated in Fig. 4, except that the supplemental tissue leaf 11 is omitted, so that four records are made at one writing.

Operations.—Referring now more particularly to Fig. 5, and assuming the various leaves to be flattened out into operative position, and inscription to be made on the original leaf 3, this inscription will be transferred to the duplicate leaf 5, the triplicate leaf 6 and the quadruplicate leaf 4, each of which leaves will receive the impression direct. There will thus be provided four direct copies on opaque paper. After inscription the original and duplicate leaves 90 are turned back (to the right in Fig. 5), where they will be received and be supported by the prolonged portion 31 of the backing 13. Thereupon the transfer leaf 18 is turned to the side, the triplicate leaf 6 is 95 grasped and thrown back (to the right, Fig. 5), whereupon the four leaves 3, 4, 5 and 6 may be readily torn from the stub along the weakened line 8.

After removal, the transfer leaf 17 will be 100 found lying upon the next set of record leaves whereupon, by reversal of the operation just described, the book may be set for subsequent inscription.

The operation of the modification illustrated in Fig. 4 is in the main similar to that set forth in connection with Fig. 5. By the provision of the supplemental tissue leaf 11, however, five records are made at one writing. The various leaves may be 110 torn apart and distributed as desired. In tearing the leaves apart along the fold lines, which are preferably weakened, the tissue leaf 11 will remain attached to the original leaf 3, but may subsequently be torn therefrom as will be understood.

The operations of the forms illustrated in Figs. 1 and 3 are the same as above explained except that one of the supplemental leaves 16, whether coming from the bound end of the pad or from the side thereof, will be interposed between the transfer leaf section 20 and the triplicate record leaf 6, so as to receive the inscription on its under face. In this modification the supplemental leaves 16 are intended to be temporarily retained in the book while the leaves of the main pad are distributed as desired. After all the leaves of the book have been used the supplemental pad of leaves 16 may be removed in 120 125 130

pad form and stored away for reference. It is to be understood that the hinged extensions 14 and 22, may be of sufficient length to form a cover for the main pad 1, when 5 folded into place thereupon.

Thus by the above described construction are accomplished among others the objects hereinbefore referred to.

As many changes could be made in the 10 above construction and many apparently widely different embodiments of this invention could be made without departing from the scope thereof, it is intended that all matters contained in the above description or 15 shown in the accompanying drawings shall be interpreted as illustrative and not in a limiting sense.

It is also to be understood that the language used in the following claim is intended to cover all of the generic and specific features of the invention herein described, and all statements of the scope of the invention which, as a matter of language, might be said to fall therebetween.

Having described my invention, what I 25 claim as new and desire to secure by Letters Patent is:

A sales book comprising in combination a

back, two pads bound to said back adjacent to each other, with the free ends of the leaves 30 extending in opposite directions, said pads being sufficiently spaced to permit the back to be folded to superpose the pads, one of said pads comprising a set of superposed leaves, and the other comprising a plurality 35 of sets of leaves, each set comprising four leaves attached together end to end to form a strip, said strip being folded to superpose the third and fourth leaves upon the second and first respectively, and being folded a 40 second time to bring all four leaves of the set in registry with each other, the first leaf of each set being extended beyond the others to form an extension by which the sets are bound together in the pad, said pad being 45 pivoted to said support at the end opposite said binding, and a carbon strip bound within the pad above the record leaves and of a length equal to two of said record leaves, whereby it may be folded to extend between 50 the record leaves, and a carbon sheet attached to the back at the side of said second mentioned pad.

In testimony whereof I affix my signature.

EDWARD KIRBY BOTTLE.
